(57) CLAIM

The ornamental design for a hair brush with retractable handle, as shown and described.

DESCRIPTION

FIG. 1 is a top, front and left side perspective view showing my new design, with the handle retracted;

FIG. 2 is a top plan view thereof;

FIG. 3 is a front elevational view thereof;

FIG. 4 is a right side elevational view thereof, the left side elevational view being a mirror image thereof;

FIG. 5 is a rear elevational view thereof;

FIG. 6 is a bottom plan view thereof;

FIG. 7 is a top, front and left side perspective view showing my new design, with the handle extended;

FIG. 8 is a front elevational view thereof;

FIG. 9 is a right side elevational view thereof, the left side elevational view being a mirror image thereof; and,

FIG. 10 is a rear elevational view thereof.

FIG. 2 shows the top plan view of my new design, and FIG. 6 shows the bottom plan view of my new design, with the handle either retracted or extended.
